DOG BRUSH

Jerry Remijas, Chicago, Ill., assignor to Corporate Products Research, Inc., Chicago, Ill.

Filed Sept. 6, 1974, Ser. No. 506,281

Term of patent 14 years

Int. Cl. D30—99

U.S. Cl. D30—40

FIG. 1 is a front elevational view of a dog brush showing my new design;

FIG. 2 is a bottom plan view; and

FIG. 3 is a right side elevational view.

The surfaces not shown are plain and unornamented.

I claim:

The ornamental design for a dog brush, substantially as shown and described.
